UNITED STATES PATENT OFFICE.

AXEL SUNDBORG, OF SACRAMENTO, CALIFORNIA.

COMBINATION STEP PLATE AND LUGGAGE CARRIER.

Application filed July 19, 1926. Serial No. 123,262.

This invention relates to automobile accessories, my principal object being to provide a device to be permanently mounted on the car and designed so as to function both as a step-plate on the running board as well as a luggage carrier when desired.

Step-plates, as is well known, add a smart touch to the appearance of a car and in addition are useful in preventing the wear of the running board covering. Luggage carriers, especially in these days of camping and other long distance trips, are almost a necessity at one time or another on practically every pleasure car. I am aware that luggage carriers are now made so that they may be folded down onto the running board when not in use. Such carriers, however, are then unsightly and in the way of the feet of the persons entering or leaving the car. As a result it is very seldom that such carriers are permanently left in place, but are usually removed after each individual trip. It frequently happens, however, that a luggage carrier is needed when its use has not been foreseen, and having been left elsewhere is not available when wanted. My device is also of a foldable nature but is so designed that when folded a serviceable and neat appearing step-plate arrangement is provided, and when unfolded a luggage carrier of generous capacity is had. The device is also arranged so that it is but the work of a few seconds to fold or unfold the same. It is also but the work of a few minutes to initially install the device after which it need never be disturbed.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a fragmentary perspective outline of a motor vehicle showing my attachment applied to the running board in folded or step-plate forming position.

Fig. 2 is a similar view showing the attachment unfolded and in position to serve as a luggage carrier.

Fig. 3 is a fragmentary longitudinal section of the attachment folded.

Fig. 4 is a fragmentary transverse section of the attachment also folded.

Fig. 5 is a perspective view of the device as made for use for a single door car.

Referring now more particularly to the characters of reference on the drawings, and particularly at present to Figs. 1 to 4, the numeral 1 denotes the side of the body of a car having longitudinally spaced doors 2 and a running-board 3 extending longitudinally of the car a certain distance below the bottom of the doors.

My combination attachment for use in connection with such a door arrangement comprises a pair of plates 4 of suitable material and dimensions (depending upon the width of the running board on which they are to be mounted) spaced apart so as to be substantially in transverse alignment with the doors. These plates are rigidly connected together by longitudinal strips 5 or similar members. The inner ends of the plates terminate adjacent the vertical back plate 6 of the running-board and are bent upwardly somewhat at such termination as at 7 to form a narrow neck plate arrangement. At their outer ends the plates have longitudinal rods 8 projecting therethrough and therebeyond, the outer ends of these rods being turnable in eyes 9 secured to the running board adjacent the outer edge thereof. The plates at said outer end also have right angled flanges or projections 10 extending lengthwise thereof. When the plates are horizontally disposed these flanges are upstanding and then serve as dirt scrapers for the feet. The flanges are also disposed relative to the hinge or pivotal connection of the plates with the running board so as to form stops to prevent outward and downward tipping of the plates beyond a vertical position when said plates are raised as shown in Fig. 2.

Hinged onto the opposed side edges of the plates 4 are wings 11, substantially the same area as said plates and adapted to fold closely against the back faces of the same.

When the plates 4 are horizontally disposed with the wings 11 thereunder, the structure then rests firmly against the running board and the plates 4 then serve as step-plates. The plates are of fairly substantial character and their outer faces are preferably corrugated or deeply nurled so as to offer a non-slip footing. The nurling or corrugating is also so disposed that the

plates as a whole present a neat appearance. The wings may be of lighter material but should also be rigid and substantial so as to be able to withstand hard service when unfolded and in use.

To positively maintain the plates in a horizontal position and prevent any vibratory movement or undesired raising of the same, I mount studs 12 in the running board adjacent and outwardly of the opposite sides of the plates at their inner ends. Clamping members 13 are turnably and removably fitted over the studs and are arranged to engage the running board at one end and to overhang and engage the plates 4 at the other end. The clamps are maintained in clamping engagement by wing nuts 14 or the like on the studs.

When the clamps are removed, the plates 20 4 raised and the wings opened out to a luggage carrying position, the studs then serve as stops to prevent further outward movement of the wings. The latter being independently movable one or the other may be 25 left folded if a very long article, projecting beyond the plates 4, is to be carried.

If the car is of the single door type only one plate 4^a would be used as shown in Fig. 5. The wings 11^a are then both mounted at 30 the opposite ends of the one plate. The plate in this case is preferably longer than those used in the first described type so as to provide sufficient luggage carrying space between the wings when the latter are unfolded.

In both forms of the device, each wing is provided with an orifice 15 near its lower 40 inner end when unfolded, so that when in this position, the end of the adjacent clamping member 13 may be projected through the orifice. When the nut 12 is then turned down, the wing is held against undesired folding movement.

From the foregoing description it will be 45 readily seen that I have produced such a device as substantially fulfills the objects of the invention as set forth herein.

While this specification sets forth in detail the present and preferred construction 50 of the device, still in practice such deviations from such detail may be resorted to as do not form a departure from the spirit of the invention, as defined by the appended claims.

Having thus described my invention what I claim as new and useful and desire to secure by Letters Patent is:

1. A combination step-plate and luggage carrier for motor vehicles comprising a plate member to lie superimposed on the running board of the vehicle, means for mounting the plate at its outer edge onto the running board in hinged relation thereto whereby to permit the plate to be raised to a vertical position, and a flange along the outer edge of the plate, said flange lying in an upstanding position when the plate is horizontally disposed to then serve as a scraper, and when the plate is vertically disposed, bearing against the upper face of the running board to prevent outward turning of the plate beyond a vertical position.

2. A combination step plate and luggage carrier for motor vehicles comprising a plate member to lie superimposed on the running-board of the vehicle, means for mounting the plate at its outer edge onto the runningboard in hinged relation thereto, whereby to permit the plate to be raised to a vertical position, a wing plate hinged to one side of the plate member and adapted to fold against the back face thereof, and clamping means mounted on the runningboard to both engage the plate when horizontally disposed and the wing when the latter is outstretched.

3. A combination step plate and luggage carrier for motor vehicles comprising a plate member to lie superimposed on the running-board of the vehicle, means for mounting the plate at its outer edge onto the runningboard in hinged relation thereto, whereby to permit the plate to be raised to a vertical position, a wing plate hinged to one side of the plate member and adapted to fold against the back face thereof, and clamping means for said plate and wing comprising a horizontal member, a fixed stud on which said member is turnably mounted, and a screw on the stud to engage said member, the latter when the plate is horizontally disposed being adapted to overhang said plate, and when the latter is raised and the wing outstretched being arranged at one end to enter an orifice provided therefor in the wing.

In testimony whereof I affix my signature.

AXEL SUNDBORG.
